(57) **CLAIM**

The ornamental design for a blanket with viewing lens, as shown and described.

DESCRIPTION

FIG. 1 is a front perspective view of a blanket with viewing lens;

FIG. 2 is a front view of the blanket with viewing lens;

FIG. 3 is a rear view of the blanket with viewing lens;

FIG. 4 is a top view of the blanket with viewing lens;

FIG. 5 is a bottom view of the blanket with viewing lens;

FIG. 6 is a first side view of the blanket with viewing lens;

FIG. 7 is a second side view of the blanket with viewing lens;

FIG. 8 is a perspective view of the blanket with viewing lens being used;

FIG. 9 is a front perspective exploded view of the blanket with viewing lens;

FIG. 10 is a detail view from FIG. 2 of the blanket with viewing lens;

FIG. 11 is a detail view from FIG. 3 of the blanket with viewing lens;

FIG. 12 is a detail view from FIG. 4 of the blanket with viewing lens;

FIG. 13 is a detail view from FIG. 5 of the blanket with viewing lens;

FIG. 14 is a detail view from FIG. 6 of the blanket with viewing lens;

FIG. 15 is a detail view from FIG. 7 of the blanket with viewing lens; and,

FIG. 16 is a detail view from FIG. 9 of the blanket with viewing lens.

The broken lines in FIG. 8 depicting the environment of a bed and a user; show the design in a state of use, and form no part of the claimed design. The remaining broken lines in the drawings depict boundary lines of the detail views and form no part of the claimed design.

1 Claim, 11 Drawing Sheets
